UNITED STATES PATENT OFFICE.

LESLIE S. HACKNEY, OF ST. PAUL, MINNESOTA.

COOLING SYSTEM FOR INTERNAL-COMBUSTION ENGINES.

1,075,351.

Specification of Letters Patent. Patented Oct. 14, 1913.

Application filed May 31, 1912. Serial No. 700,656.

To all whom it may concern:

Be it known that I, LESLIE S. HACKNEY, a citizen of the United States, residing at St. Paul, in the county of Ramsey and State 5 of Minnesota, have invented new and useful Improvements in Cooling Systems for Internal-Combustion Engines, of which the following is a specification.

My invention relates to improvements in 10 cooling systems for internal combustion engines, and is particularly adapted for use on tractors.

The common types of combustion engines are inefficient for heavy work because the 15 ordinary systems of air or water cooling for the cylinders are not adequate for the purpose.

My object is to provide efficient and economical means for cooling such engines as 20 hereinafter particularly pointed out and distinctly claimed. To this end as will be seen, I utilize both water and air to secure the desired result.

In the drawings, Figure 1 is a plan view 25 illustrating an engine with the top of its hood removed and showing various parts of my improved cooling system; Fig. 2 is a side elevation of the same with one side of the hood and one side of the air casing removed, 30 Fig. 3 is a detail end elevation of one of the engine cylinders and its adjacent baffle-plate.

In the drawings, I have used the reference numeral 10 to indicate the supporting 35 frame for an internal combustion engine 11, which comprises a plurality of water-jacketed cylinders 12. The radiator 13 on the forward end of the frame is connected with said cylinders 12 in the ordinary manner 40 and forms the forward end of the engine 11. This hood comprises a top 15, bottom 16, sides 17 and rear wall 18. An air casing 14^a is arranged within the hood to completely inclose the engine 11. This casing 45 is formed by sheet metal sides 14^b extending from the radiator 13 to the rear wall 18 of the hood, together with the top 15 and bottom 16 of the hood 14. The power driven fan 19 is arranged within the air casing 14^a and adjacent to the radiator 13. This fan is designed to draw air through the 50 radiator and force the same backward into the air casing and around the cylinders. A second power driven fan 20 is arranged beneath the hood 14 and is inclosed by the

casing 21, which communicates with the outlet port 22 formed in the bottom and at the rear of the air casing. Said fan, 20, serves to expel heated air from the interior of said casing. This arrangement of a fan 60 for supplying the air casing with fresh air, co-acting with a second fan for removing the heated air from said casing causes a rapid circulation of air and co-operates with the water to cool the cylinders. 65

I provide each of the water-jacketed cylinders 12 with a plurality of horizontally arranged flanges 23 which radiate heat from said cylinders and aid materially in cooling said cylinders and the water contained therein. In order to prevent dead air spaces between and about the cylinders, baffle-plates 24 are arranged between the sides 14^b of the casing and alternate engine cylinders 12. These plates direct the main current of air 70 in and out between said cylinders as indicated by arrows in Fig. 1 of the drawings. A part of the current of air produced by the fans 19 and 20 passes between the flanges 19 of each cylinder 12 and the adjacent baffle-plate 24. This supplementary current 75 of air, together with the main current, constantly supplies the entire peripheries of the cylinders 12 and flanges 23 with relatively cool air. A series of perforations 80 is formed on the edge of each baffle-plate 24 adjacent to the side wall 14^b of the casing 14^a and is arranged to permit the passage of air through said baffle-plates to further eliminate dead air spaces in the pockets 85 between the sides of the casing and backs of the baffle-plates 24. 90

My improved system permits the use of a relatively small volume of water and thereby cheapens construction and eliminates unnecessary weight. 95

Having described my invention what I claim as new and desire to protect by Letters Patent is:

1. The combination with a combustion 100 engine having a plurality of cylinders inclosed within an air casing and provided with an air inlet passageway at one end and an outlet port at the other, of a fan adjacent to the inlet passageway, a second fan 105 adjacent to said outlet port, said fans being adapted to cause a circulation of air through said casing, and baffle-plates within the casing extending from the sides thereof to alternate cylinders of said engine for direct- 110

ing the current of air between and about said cylinders and from one side of the casing to the other.

2. The combination with a combustion engine having a plurality of cylinders and inclosed within an air casing provided with an air inlet passageway at one end and an air outlet port at its other end, of a plurality of horizontal flanges on each of said cylinders, a fan adjacent to said inlet passageway and a second fan adjacent to said outlet port, said fans being adapted to cause a circulation of air through said air casing and perforated baffle-plates within the casing extending from the sides thereof to alternate cylinders of said engine adapted to divert the main current of air from one side of the casing to the other and to permit a lesser current of air to pass directly through said casing.

3. The combination with a combustion engine having a plurality of water-jacketed cylinders in communication with a source of water supply and inclosed within an air casing provided with an air inlet passageway and an air outlet port, of flanges on said cylinders, a power driven fan adjacent to the inlet passageway, a second power driven fan adjacent to said outlet port and baffle-plates within the casing extending from the sides thereof to alternate engine cylinders, said fans being adapted to cause a rapid circulation of air through said casing for cooling said source of water supply and said cylinders.

4. The combination with a combustion engine having a plurality of water-jacketed cylinders in communication with a source of water supply and inclosed within an air casing provided with an air inlet passageway and an air outlet port, of a power driven fan adjacent to the inlet passageway, a second casing beneath said hood and communicating with said outlet port, a second power driven fan in said casing and baffle-plates within said first-mentioned casing extending from the sides thereof to alternate engine cylinders, said fans being adapted to

cause a rapid circulation of air through said casing.

5. The combination with a combustion engine having a plurality of water-jacketed cylinders in communication with a source of water supply and inclosed within an air casing provided with an air inlet passageway at one end and with an air outlet port at its other end, of a plurality of horizontal flanges on each of said cylinders, a fan adjacent to said inlet passageway and a second fan adjacent to said outlet port, said fans being adapted to cause a circulation of air through the casing and perforated baffle-plates within said casing extending from the sides thereof to alternate cylinders of said engine.

6. The combination with a combustion engine having a plurality of cylinders, water jackets therefor in communication with a source of water supply and inclosed within a hood, said jackets being formed with horizontal flanges thereon, of an air casing surrounding said engine, said casing comprising side walls adjacent to the engine cylinders and extending from the base to the top of the hood, an inlet passageway at one end of said casing, an outlet port at the opposite end of said casing, a fan adjacent to said inlet passageway, a second fan adjacent to said outlet port, said fans being adapted to cause a circulation of air through the casing and perforated baffle-plates within said casing extending from the sides thereof to the flanges of alternate cylinders of said engine, said plates being adapted to divert the main current of air from one side of the hood to the other and to permit a lesser current of air to pass directly through said perforations and between said plates and cylinders.

In testimony whereof, I have signed my name to this specification in the presence of two subscribing witnesses.

LESLIE S. HACKNEY.
